FASTENING-INSERTING MACHINE

John F. Standish, Winthrop, Mass., assignor to
United Shoe Machinery Corporation, Paterson,
N. J., a corporation of New Jersey

Application June 15, 1932, Serial No. 617,433

45 Claims. (Cl. 1—32)

My invention relates to machines for inserting fastenings in such work as shoes, it being especially applicable to those machines by which heels are attached by nails driven from within the

shoes. In apparatus of the character above mentioned, to operate upon work of different sizes, it is a common practice to provide for the insertion of the attaching nails at different distances from the rand-crease, this being accomplished by adjusting toward and from the central vertical axis of the jack upon which the work is supported tubes containing the nail-drivers. It is also customary, when a loading device is employed to transfer the nails from a point of supply to a jack, to alter the nail-holding passages of said device by supplying different loader-blocks to correspond to the particular nailing design for which the jack is arranged.

An object of my invention is to obtain a change at the transferring device, which will produce agreement between its fastening- or nail-delivering passages and the receiving passages of a work-support without thought or effort on the part of the operator. To bring this about, I combine with a jack or work-support a loader or transferring device traveling between a nail-receiving position and a nail-delivering position at the work-support and provided with movable holding members, in which are passages for nails or other fastenings to be inserted, together with automatic means for moving the members upon the transferring device. Preferably, this movement is effected by contact with elements of the support, as by engagement of the nail-holders upon the loader with tubes variable in location upon the jack, the movement of the holders being resisted by springs which urge them to normal positions. Each holder of the nail-supplying system, whether or not it be an element of the loader, may have a nail-retaining member extending into its nail-passage and being movable to free the nails. As illustrated, the retaining members are moved similarly to the holders, acting to free the supported nails by contact with an element of the jack. By this arrangement, the loader may be caused to receive in the passages nails from a supplying means, such as the foot-plate of a distributor, in an unvarying relation; and then, as the loader travels into direct co-operation with the jack, its holders, by successive contact with the nail-receiving tubes of said jack, are retained in registration therewith, the holders being automatically brought into conformity with the jack-tubes, and the nails released from the

retaining members to enter said tubes. Since the nailing designs are of different dimensions transversely of the jack as well as from front to rear, certain of the holders are mounted upon the loader for both bodily and angular movement. In the present instance, those holders having such a compound movement are each provided with an inclined contact-surface, which, upon engagement with a nail-receiving member or jack-tube, produces the desired angular movement, final registration with the tube being effected by a surface upon the holder in which the inclined surface terminates. Apart from the manner of co-operation with the work-support or jack, patentable novelty is believed to exist in certain aspects of the nail-loader per se, as one in which nail-holding members are yieldably urged to normal positions, so they are capable of adapting themselves to different nailing designs. The preferred manner of attaining this conformity is by arranging certain of the holders, as those for the breast and rear nails, to slide upon the body-portion of the loader, while others, as those for the side nails, are pivoted upon slides. Movable shutters projecting into the passages of the holders normally support the nails.

Another object of this invention is to support the work advantageously for the insertion of the nails. In the present embodiment of the invention, in which a jack is provided with nail-tubes movable to give different nailing designs, these tubes have their upper extremities, with which the work contacts, lying generally in a plane inclined downwardly from front to rear of the jack. This not only causes the rear nail driven into the heel-seat of a jacked shoe, as through a vertical tube, to enter the heel to be attached at an inward inclination, so it is less likely to emerge through the rear wall when the heel is tapered heavily from the heel-seat-end to the tread-end, but also is particularly adapted for co-operation with the loading or transferring mechanism previously outlined and in which delivery-openings of the nail-holders occupy a plane similarly inclined. When these instrumentalities are brought together, the holders of the loader may pass freely over the portions of the jack-top in which are openings with which they are not to register, and reach, without interference, the openings to which they are to deliver.

In the accompanying drawings is illustrated one of several possible forms of my invention. Here,

Fig. 1 is a side elevation of a jack and the di-

110

rectly co-operating portion of nail-loading mechanism of a heel-attaching machine;

Fig. 2 shows said loading mechanism similarly in co-operation with the foot-plate of a nail-distributor;

Fig. 3 is a plan view of the loading mechanism with the elements arranged as when in co-operation with the jack;

Figs. 4 and 5 are vertical longitudinal sections 10 on the lines IV—IV and V—V, respectively, of Fig. 3;

Figs. 6 and 7 are like sections upon the line 15 VII—VII of Fig. 3, the elements being in positions in the two views which they successively assume;

Fig. 8 is a transverse vertical section through the rear nail-holder;

Fig. 9, a full horizontal section on the line 20 IX—IX of Fig. 5;

Fig. 10, a broken perspective view of the forward portion of the loader;

Fig. 11, a similar view of the jack-top; and

Fig. 12, a detail in broken perspective illustrating especially the shutter associated with 25 the breast-nail-holder of the loader.

At 10 (Figs. 1 and 11) appears the body of a jack designated as a whole by J and adapted for the inside nailing of heels. Generally it may be arranged as is that of Letters Patent of the 30 United States No. 1,545,575, Standish, July 14, 1925. That is, it contains a reciprocatory plunger 12 carrying nail-drivers 14 operating in tubes shown as five in number, there being two breast-tubes 18, 18 formed as a unit, two side tubes 20, 20, 35 and one rear tube 22. In these tubes heel-attaching nails may be held resting upon the ends of the drivers. The tubes are variable in position toward and from each other in the manner described in previously mentioned Letters Patent, 40 a screw 23 being used to move a cam-plate 25 and thereby adjust simultaneously all but the rear tube, this being clamped separately. Of course, any other desired adjustment may be employed. The tubes may thus be arranged in accordance 45 with different nailing designs. To obtain a close crease, it is desirable to locate the points of insertion of the nails close to the peripheries of the heels, and as the extreme pitch of many heels in women's work tends to cause the rear nails to 50 emerge through the side walls, many heels are thus spoiled. I therefore prefer to incline at 24 the surfaces of the upper ends of the jack-tubes which contact with the heel-seat of the shoe to be heeled, the inclination being generally in a 55 plane diverging downwardly from the horizontal from front to rear of the jack. The breast and side tubes may also have their surfaces 24 laterally inclined, downwardly and outwardly. This not only directs the nails inwardly away from 60 the heel-wall, but also makes the tread-surface of the heel more nearly horizontal, giving more effective engagement therewith of the usual pressure-abutment which resists the nail-driving forces. To hold up the forepart of a shoe being 65 heeled, so the heel-seat may contact evenly with the inclined tube-ends, a rest 26 is provided, this being adjustably pivoted at 28 upon a vertically movable slide 30 secured to the front of the jack by a slot-and-screw connection 32. The rest may, 70 by its connecting means, be varied in position both as to height and inclination.

The attaching nails may be supplied to the jack by loading mechanism L, of which only the forward portion is illustrated herein. This mechanism has a horizontal reciprocatory slide 36 car-

rying at its end toward the jack a frame 38 to receive a loader-block 40 in which are contained the nails for delivery to the jack J, in a manner which will be later explained. Delivery to the loader is made from a foot-plate 42 (Fig. 2) through passages in which nails are fed in successive groups by way of tubes 44 leading from a distributor (not shown). The loader-block containing the nails may be carried from its receiving position beneath the foot-plate to its delivering position over the jack-tubes and reversely by such a mechanism as is described in Letters Patent of the United States No. 1,785,928, Benjamin, December 23, 1930, and which is under the control of the operator.

The loader-block 40 has projecting from the opposite sides of its upper portion flanges 46 resting upon the frame 38 (Fig. 10), it being releasably held against upward displacement by latches 48, 48 (Fig. 3) secured to it and engaging the under side of the frame. The block or body-portion has extending through its forward extremity a wide slot 50 while at the rear is a narrow central slot 52 and two parallel side slots 54, 54. The end of the slot 50 is closed by a retaining bar 56 and the rear slots are similarly closed by a bar 58, both of these bars being secured to the ends of the block. Movable in the slot 50 is a holder 60 for the two breast-nails. This holder is in the form of a slide having guide-flanges 62 105 extending above and below the block. From the body of the slide rises a portion 64 containing, together with the slide, vertical passages 66, 66 for the breast-nails, these being preferably in unvarying relation to each other. The upper extremities of the holder-passages may have somewhat enlarged throats 68 to facilitate the introduction of the nails, and, to permit close approach for nail-delivery, the holder-wall about the lower ends of the passages is inclined at 70 to correspond to the inclination of the jack-tubes at 24. The delivery-portions of the associated holders are similarly formed. The slide 60 is held normally forward, to an extent permitted by its contact with the bar 56, by a helical spring 72 (Figs. 115 4, 6 and 7) contained within a recess in it and in an alined recess in an opposed surface of the block 40. To hold the nails in each passage until, because of registration between said passage and a jack-tube, they are ready for delivery, each 120 passage is provided with a movable retaining member or shutter 74, preferably furnished by a projection from the lower edge of a movable carrier-plate 76 which may be guided by arms 75, 75 (Figs. 3 and 12) extending toward the front 130 of the plate and movable in slots 77 (Fig. 10) in opposite sides of the holder 60. The carrier-portion of the shutter has an upward extension 78 which is supported by a screw 80 upon the holder-portion 64 to move in a recess therein. This 135 movement allows the projections 74 to either extend into the corresponding passages 66 to support the contained nails, or to be shifted rearwardly to free said nails for delivery to the jack-tubes 18. The carrier-plate is shown as urged 140 yieldably toward the front of the loader by a spring 82, interposed between the head of a screw 83 threaded into the plate and the end of a counter-bore in the holder 60 in which said screw-head is movable. Both retaining projections 74 are shifted within the passages 66 to release the nails by the engagement of a projection 84 depending from the center of the plate 76 and contacting with a wall 86 between the jack-tubes 18, 18. This contact occurs when 150

- the slide 36 brings forward the loader-block 40 with its contained nails. After the shutters have been opened, the holder 60 may yield, compressing the spring 72. The manner in which the loader-passages register with the jack-tubes and of release of the nails from the passages will be stated in greater detail after the arrangement of the rear and side nail-holders of the loader has been described.
- 10 In the center rear slot 52 in the block 40 a holder 90 for the rear nail is movable (Figs. 4 and 8). This, like the holder 60, consists of a slide having guide-flanges 92 contacting with opposite sides of the block and under the influence of a spring 93, similar to the breast-slide-spring 72, by which it is urged inwardly. The outer extremity of the spring 93 may be received by a recess in the bar 58. The holder 90 contains in it and in an upward extension 94 a nail-receiving passage 96, normally closed at its lower extremity by a retaining projection 98. The projection is formed upon a shutter-body or slide 99 arranged to reciprocate in a horizontal bore at the bottom of the holder. It is forced yieldably forward into the passage 96 by a spring 100 contained in a recess within the slide and backed by a screw 102 threaded into the holder. A pin 104 lying in a slot in the holder limits the forward travel of the shutter. A wall 106 of the shutter strikes the rear of the jack-tube 22 when the loader travels forward, opening the shutter against the force of the spring 100 to release the nail. This is followed by the yield of the slide 90 against the spring 93.
- 15 While for the breast-nail-holder and rear nail-holder only rectilinear movement from front to rear of the loader-block is necessary, the side nails must also be varied in position laterally to allow them to conform to different designs. The two side holders 108, 108 and their carrying means may be the same, except that their lateral movement is opposite. Consequently, but one will be described. Movable in each loader-block-slot 54 is a holder-slide 110 forced normally forward by a spring 112 interposed between it and the bar 58. Rotatable in the forward extremity of the slide is a vertical spindle 114 (Fig. 5), and clamped against movement about the upper end of the spindle is a horizontal arm 116 of the holder 108, in which arm is a nail-receiving passage 118. Formed upon the holder at the outer side of the passage is a contact-arm 120 provided with an inner vertical surface or wall 122 inclined outwardly and forwardly from the direction of movement of the slide 110 (Figs. 3 and 9). At its inner end the wall 122 terminates in a curved wall 124 lying transversely of the path of the slide. Projecting through the wall 124 into passage 118 is the nail-retaining portion 126 of a sliding shutter 128. The construction and operation of this shutter may be identical with that of the rear holder 94 and needs no further explanation. A scissors-spring 130 is shown joining the arms 116 to urge them normally toward each other. As the loader-block moves into co-operation with the jack J each surface 122 will strike one of the jack-tubes 20, whatever may be the adjustment of said tube, turning the holder 108 outwardly about the axis of the spindle. When a wall 132 (Fig. 5) of the shutter 128 reaches the jack-tube, it contacts therewith to open said shutter and release the nail. Finally, upon completion of the shutter-movement, the curved surface 124 strikes the tube, the slide 110 then yielding against the
- spring 112. It will thus be seen that there is imparted to each passage 118 a compound angular and rectilinear movement, which permits it to adapt itself to different side-nail locations both longitudinally of the heel-seat and transversely thereof.
- 20 Fig. 2 of the drawings shows the loader L in its nail-receiving position beneath the foot-plate 42 of the distributor, while in Figs. 1, 3, 4, and 10 the elements are positioned as when in direct co-operation with the jack J for delivering the nails to the tubes thereof. The foot-plate-passages have an unvarying relation and the nail-holder passages of the loader-block 40 register with these whenever a load of nails is received, regardless of the adjustment of the jack-tubes for different nailing designs. This normal foot-plate- and loader-block-passage arrangement may be such that, of the latter, the breast-passages 66, 66 correspond to the maximum design or are most widely separated from the center of the group, while the passages 96 and 118, 118 are in accordance with the minimum design to be nailed. The breast-holder 60 is maintained by the spring 72, the rear holder 90 by the spring 93, and the side holders 108, 108 by the springs 112 and 130 to thus locate the passages. Assume that a heel is to be attached calling for the employment of the smallest nailing design, and that the loader-block 40 is beneath the foot-plate 42, having received therefrom a load of nails which rest heads down upon the retaining projections 74, 98 and 126 of the shutters. Before the operator places a shoe upon the jack J and applies thereto the heel to be attached, he causes the loading mechanism to advance from its receiving position in the manner described in the Benjamin patent. When it reaches the jack, the lower portions of the holder 60, including the depending shutter-projection 84, pass freely over the jack-tubes 20 and 22 because of the downward inclination of these from front to rear of the jack. The projection 84 contacts, however, with the wall 86 of the breast-section of the jack and causes the shutter 76 to be forced back, the spring 82 yielding (Fig. 7). When the loader-passages 66 have come sufficiently into registration with the jack-tubes 18, this action will have withdrawn the retaining projections 74 from beneath the nails which they support to release said nails and permit them to drop into the tubes 18, where they rest upon drivers 14 ready for insertion. The forward travel of the loader-block continues, compression of the spring 72 allowing this, the holder being maintained stationary by the engagement of its shutter with the jack-wall 86. In this loader movement the side holders 90 pass the rear jack-tube 22 without interference and the walls 122 of the holder-arms 120 contact with the jack-tubes 20. This causes each side holder to move somewhat outwardly, turning about the axis of the spindle 114 until the shutter-wall 132 strikes the jack-tube. The shutter 128 is then displaced against its spring to withdraw the nail-retaining projection 126 from the corresponding passage 118 and discharge the supported nail into the jack-tube (Fig. 9). Further forward movement of the loader-block is made possible by the yield of both the springs 72 and 112. Contact of the wall 106 upon the shutter 99 with the rear jack-tube 22 releases the contained nail from the loader-passage 96 to enter said tube (Fig. 4) and the loading operation is completed. Forward travel of the loader, how-

ever, is continued sufficiently to compress the spring 93, ensuring full alinement of the passage 96 with the jack-tube. The loader-block is thereupon withdrawn by its slide 36 from above the jack to beneath the foot-plate 42. When the holders with their nail-retaining means leave the jack-tubes, their springs restore said holders and retaining means to their initial positions, and the mechanism is ready to receive and deliver another load of nails to the jack. In the case of the smallest nailing just considered, the movement of the breast-nail-holder is from its normal position of maximum displacement from the center of the group of holders to the minimum necessary to bring it into conformity with the chosen nailing design. The associated side and rear tubes, however, normally correspond to this minimum arrangement and their displacement by contact with the jack-tubes is merely to insure perfect registration of all the holder-passages with the jack-tube-passages. Taking the opposite extreme, or the actuation of the holders of the loader for delivery to the maximum nailing design, the breast-holder is now moved but slightly to establish registration with the jack-tubes, while the displacement of the side and rear tubes is through the maximum distance. In this way, travel of the loader in one direction for delivery is caused to adjust nail-holders which move in different directions from a central point. For intermediate nailings, corresponding opposite movements of the breast-holder and the side and rear holders will be produced. Throughout the entire range, the action of the loading mechanism in adapting itself to different designs is entirely automatic, the holders receiving the nails from the distributor always in the same relation and then conforming to any adjustment which has been made at the jack-tubes.

While there is herein particularly disclosed only the automatic individual adjustment to different nailing designs of nail-holders associated with a loader, it is to be understood that my invention also comprehends a variation in the positions of jack-tubes to conform to diverse arrangements of nail-holders of a loader. Further, the adjustment of the loader nail-holders may be effected by a member common to all and manually.

Having thus described the invention, what I claim as new and desire to secure by Letters Patent of the United States is:

1. In a fastening-inserting machine, the combination with a work-support, of a transferring device movable from a fastening-receiving position separated from the work-support to a fastening-delivering position at said work-support and provided with movable members in which are fastening-holding passages, and automatic means for moving the members upon the transferring device.
2. In a fastening-inserting machine, the combination with a work-support having fastening-inserting means variable in position, of fastening-supplying means having passages occupying unvarying positions, and a transferring device provided with members in which are fastening-holding passages normally corresponding to the passages in the supplying means, the members being movable to bring their passages into conformity with the inserting means.
3. In a fastening-inserting machine, the combination with a work-support having fastening-inserting means variable in position, of fastening-supplying means having passages occupying

unvarying positions, and a transferring device provided with movable members in which are fastening-holding passages normally corresponding to the passages in the supplying means, the members contacting with the support and being moved by such contact upon the transferring device.

4. In a nailing machine, the combination with a jack having movable nail-receiving members, of a loader movable to deliver nails to the jack and having nail-holders movable upon it by contact with elements of said jack.
5. In a nailing machine, the combination with a jack having movable nail-receiving tubes, of a loader movable to deliver nails to the tubes and having nail-holders movable upon it by contact with the jack-tubes during the travel of the loader.
6. In a nailing machine, the combination with a jack having movable nail-receiving members, of a loader movable to deliver nails to the jack and having nail-holders movable upon it by contact with elements of said jack, said contact being successively established for different holders.
7. In a nailing machine, the combination with a jack having movable nail-receiving members, of a loader movable to deliver nails to the jack and having nail-holders movable upon it by contact with elements of said jack, said contact being successively established for different holders and the travel of the loader continuing after contact of all the holders.
8. In a nailing machine, the combination with a jack having movable nail-receiving members, of a loader movable to deliver nails to the jack and having nail-holders movable upon it by contact with elements of said jack, and springs resisting the movement of the holders.
9. In a nailing machine, the combination with a work-support having nail-receiving passages, of a loader movable to deliver nails to the support and having nail-holders movable upon it by contact with elements of said support, said holders being arranged upon the loader to correspond to different nailing designs.
10. In a nailing machine, the combination with a jack having movable nail-receiving tubes, of a loader movable to deliver nails to the jack and having nail-holders movable upon it by contact with elements of said jack, a portion of said holders being arranged upon the loader to correspond to the minimum nailing design provided by the jack-tubes and a portion arranged to correspond to the maximum nailing design.
11. In a nailing machine, the combination with a work-support having nail-receiving passages, of a loader movable to deliver nails to the support and having nail-holders movable upon it, each holder including a movable nail-retaining member.
12. In a nailing machine, the combination with a jack having movable nail-receiving members, of a loader movable to deliver nails to the jack and having nail-holders each including a nail-retaining member movable by contact with an element of the jack.
13. In a nailing machine, the combination with a jack having movable nail-receiving tubes, of a loader movable to deliver nails to the tubes and having nail-holders movable upon it and including nail-retaining members movable by contact with the jack-tubes and thereafter allowing movement of the holders.
14. In a nailing machine, the combination with a work-support having a nail-receiving passage,

1. of a loader movable to deliver nails to the jack and having a nail-holder mounted for bodily movement and for angular movement by contact with an element of the support.

2. In a nailing machine, the combination with a jack having a movable nail-receiving member, of a loader movable to deliver nails to the jack and having a nail-holder mounted for bodily movement and for angular movement, said holder having a surface inclined with respect to the direction of bodily movement and arranged for contact with the nail-receiving member.

3. In a nailing machine, the combination with a jack having a movable nail-receiving member, of a loader movable to deliver nails to the jack and having a nail-holder mounted for bodily movement and for angular movement, said holder having a surface inclined with respect to the direction of bodily movement and terminating in a surface extending transversely of such direction of movement, the surfaces being arranged for successive contact with the nail-receiving member.

4. In a nailing machine, the combination with a jack having a movable nail-receiving member, of a loader movable to deliver nails to the jack and having a nail-holder mounted for bodily movement and for angular movement, said holder having a surface inclined with respect to the direction of bodily movement and terminating in a surface extending transversely of such direction of movement, the surfaces being arranged for successive contact with the nail-receiving member, and a movable nail-retaining member extending through the transverse surface.

5. A nail-loader comprising a body-portion movable to effect nail-transfer, nail-holders movable thereon, and means for yieldably urging the holders to normal positions.

6. A nail-loader comprising a body-portion movable to effect nail-transfer, a group of nail-holders movable thereon, and means for yieldably forcing the holders to positions corresponding to different nailing designs.

7. A nail-loader comprising a body-portion, a group of nail-holders movable thereon, and means for yieldably forcing a portion of the holders toward the center of the group and another of said holders away from such center.

8. A nail-loader comprising a body-portion, a carrier arranged to slide upon the body-portion, and a nail-holder pivoted upon the carrier.

9. A nail-loader comprising a body-portion, nail-holders movable thereon, and means common to plural holders for urging them in opposite directions.

10. A nail-loader comprising a traveling block, and a slide yieldable upon the block and provided with a nail-holding passage.

11. A nail-loader comprising a traveling block, a slide movable upon the block, and a nail-holder movable upon the slide and provided with a nail-holding passage.

12. A nail-loader comprising a traveling block, a slide movable upon the block, and a nail-holder pivoted upon the slide and provided with a nail-holding passage.

13. A nail-loader comprising a traveling block, a slide movable upon the block, and a nail-holder pivoted upon the slide and provided with a nail-holding passage, the holder having a contact-arm projecting from it.

14. A nail-loader comprising a traveling block, a slide movable upon the block, a nail-holder pivoted upon the slide and provided with a nail-holding passage, there being a curved wall adjacent to the passage and an inclined wall extending from the curved wall, and a yieldable shutter projecting through the curved wall into the passage.

15. A nail-loader comprising a traveling block, a slide movable upon the block and provided with a nail-holding passage, and a yieldable shutter projecting into the passage.

16. A nail-loader comprising a traveling block, a slide movable upon the block and provided with a nail-holding passage, and a spring interposed between the slide and block.

17. A nail-loader comprising a traveling block, a slide movable upon the block and provided with a nail-holding passage, a spring interposed between the slide and block, a movable shutter projecting in the passage, and a spring holding the shutter normally closed.

18. A nail-loader comprising a traveling block, opposite nail-holders pivotally mounted upon the block, and a spring connecting the holders.

19. A nail-loader comprising a traveling block, spaced slides movable upon the block, a nail-holder pivoted upon each block, and a spring connecting the holders.

20. A nail-loader comprising a traveling block, spaced slides movable upon the block, a nail-holder pivoted upon each block, a spring connecting the holders, and a spring acting upon each slide.

21. In a heel-attaching machine, a nail-loader comprising a body-portion, and holders for breast-nails, rear nails and side nails mounted upon the body-portion, each of said breast, rear and side nail-holders being movable independently of the associated holders.

22. In a heel-attaching machine, a nail-loader comprising a body-portion, and holders for breast-nails, rear nails and side nails mounted upon the body-portion, each of said breast, rear and side nail-holders being movable independently of the associated holders, the breast-nail-holder containing a plurality of nail-passages.

23. In a heel-attaching machine, a nail-loader comprising a traveling block in the front of which is a slot and in the rear three slots, a slide movable in the front slot and containing passages for two breast-nails, slides movable in each of the outer rear slots and each having means for carrying a side nail, and a slide movable in the center rear slot and containing a passage for a rear nail.

24. In a heel-attaching machine, a nail-loader comprising a traveling block in the front of which is a slot and in the rear three slots, a slide movable in the front slot and containing passages for two breast-nails, slides movable in each of the outer rear slots and each having a holder movable thereon and in which is a passage for a side nail, and a slide movable in the center rear slot and containing a passage for a rear nail.

25. In a heel-attaching machine, a jack provided with movable nail-tubes having their upper extremities arranged for contact with the work and lying substantially in a plane inclined downwardly from front to rear of the jack, a slide movable vertically of the jack, means ar-

ranged to fix the slide in different positions, a shank-rest pivoted upon the slide, and means arranged to vary the angle of the shank-rest on the slide.

- 5 41. In a fastening-inserting machine, the combination with a work-support having passages with fastening-receiving openings lying substantially in a plane inclined in one direction, of a transferring device provided with fastening-holders movable upon the transferring device by contact with elements of the support and delivering to the support-passages, the ends of the holders co-operating with said support-passages being inclined to correspond to the openings therein.
- 10 42. In a nailing machine, the combination with a jack provided with movable nail-receiving tubes having their upper ends lying in a plane inclined downwardly and rearwardly of the jack, of a loader movable to deliver nails to the tubes and having 20 nail-holders movable upon it by contact with said tubes and with their lower extremities inclined to correspond to the jack-tubes.

43. In a nailing machine, the combination with nailing mechanism provided with nail-passages and drivers operating therein, of nail-supplying means having nail-holders with passages movable to different positions with respect to the 80 passages of the nailing mechanism, and a nail-retaining member movable with each holder.

44. In a nailing machine, the combination with nailing mechanism, of nail-supplying means having nail-tubes movable upon the supplying means 85 to correspond to different nailing designs, and a shutter individual to each tube and movable therewith.

45. In a nailing machine, the combination with nailing mechanism, of nail-supplying means having nail-holders movable to different positions, and a nail-retaining member movable with each holder and moved upon such holder by contact of a portion of the machine.

95 JOHN F. STANDISH.
